UNITED STATES PATENT OFFICE.

THOMAS JOSEPH STURTEVANT, OF WELLESLEY, MASSACHUSETTS, ASSIGNOR TO
STURTEVANT MILL COMPANY, A CORPORATION OF MAINE.

CRUSHING-MILL.

1,072,057.

Specification of Letters Patent.

Patented Sept. 2, 1913.

Application filed May 16, 1911. Serial No. 627,598.

To all whom it may concern:

Be it known that I, THOMAS J. STURTEVANT, a citizen of the United States, residing at Wellesley, in the county of Norfolk 5 and State of Massachusetts, have invented or discovered certain new and useful Improvements in Crushing-Mills, of which the following is a specification, reference being had therein to the accompanying drawings.

10 This invention relates to certain improvements on the form of crushing mill shown and described in my Patent No. 988,403, granted April 4, 1911, and in the operation of which the material is crushed between 15 rotating crushing disks carried by shafts one of which is within the other, and the axes of which are inclined to or out of line with each other, so that when the machine is running certain parts of said disks will be constantly 20 approaching each other while the diametrically opposite parts of said disks will be constantly receding from each other, thereby causing an opening and closing crushing action of said disks as they rotate. In the 25 present improved crushing mill, as in the mill of my said patent, the eccentric bearing for the inner shaft is caused to rotate in a direction opposite to the rotation of the shafts carrying the crushing disks, and preferably at a higher speed than the speed of 30 rotation of said shafts, for the purpose of causing a comparatively rapid opening and closing crushing action of the disks while they may be rotating at a relatively low rate 35 of speed, thereby avoiding the objections incidental to a high rate of speed of rotation of the crushing disks. In the present improved crushing mill the rotating shafts and the rotating eccentric bearing are driven 40 from a single pulley, through suitable gearing, instead of being driven by separate pulleys, as in the mill of my said patent, the improved construction in the present case thus doing away with one driving belt, and 45 presenting many other mechanical advantages, as will hereinafter appear.

In the accompanying drawings Figure 1 is a longitudinal section of a crushing mill embodying the present invention, with spur- 50 gear driving mechanism, and Fig. 2 is an end view thereof looking from the right of Fig. 1. Fig. 3 is a longitudinal section of a mill embodying the present invention with

bevel gear driving mechanism, and Fig. 4 is a sectional view of the same on the line 55 4-4, Fig. 3. Figs. 5 and 6 are detail views to illustrate the bayonet joint connection of one of the crushing disks with its carrying head.

Referring to the drawings, 12 denotes a 60 suitable casing frame or support affording bearings for the hollow shaft 13 to the enlarged head portion 14 of which is bolted a spider ring 15 to which is attached, preferably by a screw threaded connection, as 65 shown, a head 16 carrying the outer rotating crushing disk 17. Inclosed within the hollow shaft 13 is an inner shaft 18 one end of which is journaled in an eccentric bearing 19; and interposed between the enlarged head portion 14 of the hollow shaft 13 and the head portion 20 shrunk on the outer end of the shaft 18, is preferably interposed a bearing piece 21. The adjacent parts of the said head portions 14 and 20 of said 75 shafts are preferably formed to afford a ball and socket bearing which takes the direct strain of the crushing disks. Attached to the head 20, in any suitable manner, preferably by bayonet joint connections, is the inner 80 crushing disk 22, which co-operates with the outer crushing disk 17. The outer disk 17 may also be attached to the head 16 by a bayonet joint connection, and in such case both disks may be attached to the heads or 85 parts by which they are carried without bolts.

The eccentric bearing 19 comprises a sleeve of iron or steel with suitably attached Babbitt metal portions engaging the inner 90 and outer shafts, the said sleeve having a head portion 23 to which is secured a gear ring 24 meshing with an idler gear 25 supported in suitable bearings in the casing part 12 and meshing with a gear wheel 26 at- 95 tached to a driving shaft 27 provided with a suitable belt pulley 28. The shaft 27 is provided with a pinion 29 meshing with a gear wheel 30 attached to the hollow shaft 13, so that said shaft will be driven from 100 the said belt pulley 28 and in a direction opposite to the direction of rotation of the eccentric sleeve 19 which is also driven from the said belt pulley 28 through the shaft 27 and the gearing just described.

105 The shaft 18 is rotated with the outer

shaft 13 through the friction resulting from the material gripped between the crushing disks 17 and 22, the frictional connection between said shafts at the ball and socket bearing between the heads 14 and 20 on the outer and inner shafts, respectively, also tending to rotate the said inner shaft with the outer shaft. The rotating crushing disks are inclosed within the casing 31 which is preferably provided with a lining 32 which will receive the impact of the crushed material centrifugally discharged from the crushing disks through the spider 15.

Any shifting or endwise movement of the eccentric bearing 19 relative to the shaft 18 is prevented by the thrust collar 33 screwed onto the threaded end of said shaft and abutting against a shoulder formed on the head portion 23 of the said bearing. This thrust collar 33 also serves to hold the ball and socket head portions of both shafts in contact, and also resists, through the thrust bearing 34 abutting against the head portion 23 of the eccentric bearing, any endwise movement of the outer shaft 13 relative to the inner shaft 18.

Bearing against the outer face of the head 23 of the eccentric bearing 19 is an oil cap or cover 35 having a central perforation, and attached to the outer portion of the casing or frame 12, adjacent to said oil cap or cover 35, is a hollow plate or cap 36 having a central recess in which is fitted a hollow plunger 37 having a concave inner end receiving the convex outer end of a tube 38 the inner convex end of which is seated in a concave recess in the oil cap or cover 35. The plunger 38 is pressed inward by a spiral spring 39. This construction provides a somewhat flexible or jointed duct for the admission of oil to the oil cap or cover 35 from which the oil will work or be forced inward to lubricate the bearings of the shafts and of the eccentric sleeve, the surplus or over-flowing oil being received in an oil receptacle or tank 40 formed by the casing or frame of the machine. The flexible or jointed duct referred to accommodates itself to movements of the rotating parts, and still preserves tight joints. The hollow plate or cap 36 is connected by a pipe 41 with an oil pump 42 driven by a belt 43 from a pulley 44 mounted on the driving shaft 27, the chamber of the pump 42 communicating with the oil chamber or receptacle 40 in such a manner as to take up the waste oil received in the chamber of said receptacle or tank and return it to the oil cap or cover 35. As the gears 24 and 30 will extend into the oil receptacle 40, below the oil level, they will serve to take up more or less oil, and carry it upward to the bearings of the driving shaft 27, and thus the different bearings of the mill will be lubricated by virtue of the oil circulation afforded by the oil pump and

the co-operating parts just described. The casing part 12, which serves as a housing inclosing the gearing, eccentric bearing and shafts, is preferably made dust-proof and oil-tight.

The hopper 45, from which the material to be crushed is fed to the crushing disks, is connected with a front part or cover 46 provided with arms 47 through which, by means of suitable clamping bolts 48, the said cover may be attached at both sides to hinge pins 49 in such a manner that by loosening or removing the clamping bolts and co-operating caps at one side of said front part or cover the latter may be swung like a door, in either direction, when it is desired to obtain access to the crushing disks or other parts housed by said front part or cover. The hopper and its inwardly extending spout is preferably mounted on its support in such a manner that it may be adjusted in or out to follow the adjustment of the outer crushing disk 17 permitted by the screw-threaded connection of the ring 16, supporting said disk, with the spider 15.

In the form of mill shown in Figs. 3 and 4 the shaft 13 is driven by a bevel gear 50 meshing with a bevel pinion 51 carried by a driving shaft 52 having a belt pulley 53, the said bevel pinion 51 also meshing with a bevel gear 54 connected with the head 23 of the eccentric bearing 19. With the exception of this driving mechanism the construction and general operation of the mill shown in Figs. 3 and 4 are the same as in the form of mill shown in Figs. 1 and 2.

Referring to Fig. 1, it will be seen that the driving pulley 28 is connected with the shaft 27 through the hub 55 by means of a breaking piece or pin 56 engaging an arm 57 on the said hub, the latter being splined to the shaft, while the belt pulley 28 is loose thereon. The pin 56, while strong enough to drive the mill under ordinary conditions, is not strong enough to resist such excessive strain as would be likely to damage the mill, and therefore if any unusual resistance occurs, such as is likely to cause breakage of any of the parts of the mill, the said pin 56 or arm 57 will break, and thus disconnect the power from the driving shaft 27. In the construction shown in Fig. 4 the connection of the driving pulley 53 with the shaft 52 is similar to that just described with reference to Fig. 1, the connecting parts being indicated by the same reference numerals.

While it is preferred to rotate the eccentric bearing 19 in a direction opposite the direction of rotation of the shafts carrying the crushing disks, it will be understood that the invention is not necessarily limited to a construction effecting this result. In the construction shown in Fig. 1 the eccentric sleeve bearing is rotated in opposition

to the direction of rotation of the disk-carrying shafts, and at a higher rate of speed, while in the construction shown in Figs. 3 and 4 the speed of opposite rotation of the eccentric bearing will be the same as the speed of rotation of the disk-carrying shafts, as will be understood from the gearing shown. In practice the speed of the hollow and solid shafts, with their attached disks, 10 is made as slow as possible, consistent with the proper centrifugal discharge of the material in process of reduction, while the eccentric sleeve bearing may be rotated in the opposite direction at a speed limited only 15 by considerations of wear and tear and cool running.

From the foregoing it will be understood that the present invention provides certain improvements over the form of mill shown 20 and described in my Patent No. 988,403, hereinbefore referred to, by which the shafts carrying the crushing disks and the rotating eccentric bearing may be driven from a single belt through a single driving pulley; 25 and it will also be understood that the lubricating means described affords facilities for keeping the bearings of the mill thoroughly lubricated without waste of the lubricating oil which can be used over and 30 over again.

The bayonet joint connections of the crushing disks 17 and 22 with their respective carrying heads 16 and 20 may be effected by providing said disks, at their 35 backs, with spaced hooked lugs 58 which, in mounting one of said disks, are first brought into register with spaces between separated lugs or projections 59 on the heads 16 and 20, and then by giving the disk a partial rotation the said hooked lugs 58 are tightly 40 wedged against the inclined faces of the lugs or projections 59 so as to lock the disk in place. The inclined faces of the lugs or 45 projections 59 are so arranged relative to the direction of rotation of the crushing disks, that, in the operation of the mill, there will be a tendency to tighten the grip of the 50 engaged lugs, and thus hold the parts securely engaged. This construction provides a readily mountable and dismountable 55 connection of the crushing disks with their carrying-heads.

Having thus described my invention I claim and desire to secure by Letters Pat- 55 ent:

1. In a crushing mill, the combination with two crushing disks, of inner and outer shafts by which said disks are carried, an eccentric bearing for said inner shaft, a 60 driving pulley, and means, including gearing, between said pulley and said bearing,

for rotating the latter independently of said shafts.

2. In a crushing mill the combination with two crushing disks, of inner and outer 65 shafts by which said disks are carried, a rotating eccentric bearing for the said inner shaft, a single driving pulley, and gear connections, driven from said pulley, for rotating said bearing and said outer shaft 70 independently of each other.

3. In a crushing mill, the combination with two crushing disks, of inner and outer shafts by which said disks are carried, a driving shaft provided with a pulley, a ro- 75 rotating eccentric bearing for said inner shaft, and gearing connecting said driving shaft with said outer shaft and said eccentric bearing and arranged to cause said shaft and bearing to rotate in opposite directions. 80

4. In a crushing mill, the combination with two rotating crushing members, of inner and outer shafts by which said members are carried, an eccentric sleeve interposed between said shafts, a thrust collar 85 on the inner shaft and by which said eccentric sleeve is held from longitudinal movement, said eccentric sleeve having a head or flanged part opposing endwise movement of the said outer shaft. 90

5. In a crushing mill, the combination with two rotating crushing members, and inner and outer shafts by which said members are carried, of an eccentric bearing interposed between said shafts and provided 95 with an annular flange which opposes endwise movement of said outer shaft, and a thrust collar screw-threaded to the end of said inner shaft and abutting against said eccentric bearing. 100

6. In a crushing mill, the combination with two crushing disks, of inner and outer shafts by which said disks are carried, an eccentric sleeve bearing for said inner shaft, a bevel gear for driving said eccentric sleeve, 105 a bevel gear for driving said outer shaft, and a single pinion to mesh with both bevel gears.

7. In a crushing mill, the combination with two crushing disks, of inner and outer 110 shafts by which said disks are carried, an eccentric bearing for said inner shaft, driving means, and means, including gearing, between said driving means and said bearing, for rotating the latter independently of 115 said shafts.

In testimony whereof I affix my signature, in presence of two witnesses.

THOMAS JOSEPH STURTEVANT.
